US0D1073348S

(12) **United States Design Patent** (10) **Patent No.:** **US D1,073,348 S**
(45) **Date of Patent:** **** May 6, 2025**

(54) **CHAIR FRAME**

(71) Applicant: **ZHANGZHOU ANQIAO INDUSTRY AND TRADE CO., LTD.**, Zhangzhou (CN)

(72) Inventor: **Anding Yang**, Zhangzhou (CN)

(73) Assignee: **ZHANGZHOU ANQIAO INDUSTRY AND TRADE CO., LTD.**, Zhangzhou (CN)

(**) Term: **15 Years**

(21) Appl. No.: **29/905,931**

(22) Filed: **Oct. 27, 2023**

(51) **LOC (15) Cl.** **06-06**

(52) **U.S. Cl.**

USPC **D6/368**; D6/708.16
